SUPPORT FOR SOUND PROJECTING APPARATUS

William C. Eaves, Elyria, Ohio, assignor to Eaves Sound Projectors, Inc., Dover, Del., a corporation of Delaware

Application April 25, 1944, Serial No. 532,620

10 Claims. (Cl. 248—183)

1

This invention relates to sound amplifying apparatus and more particularly to mountings for horns or trumpets that are associated with such apparatus.

An object of the present invention is to provide novel supporting and directional control means for a horn whereby the latter may be controlled from a remote point to direct the sound emanating therefrom in a desired direction.

Another object is to provide a horn mount embodying novel supporting and control means whereby the horn may be located at a high elevation and rotated about vertical and horizontal axes from a remote point to various positions, and locked in any of said positions.

A further object is to provide mechanism operable from a remote point for rotating a sound amplifier in opposite directions in two planes to various positions, in combination with novel means at said point for indicating the direction of rotation of said amplifier and the position occupied by the latter.

The above and further objects and novel features of the present invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a side elevation of a horn, and supporting and directional control means therefor embodying the present invention, with portions of said means broken away for purposes of clearer illustration;

Fig. 2 is an enlarged fragmentary end view, partly in section, of the horn and supporting means therefor illustrated in Fig. 1 and looking from the left of said figure;

Fig. 3 is an enlarged vertical transverse sectional view of the lower end portion of the horn supporting and directional control means, illustrated in Fig. 1 and looking from the right of the latter figure;

Fig. 4 is an enlarged vertical longitudinal sectional view of the upper end portion of the horn supporting means illustrated in Fig. 1;

Fig. 5 is a horizontal sectional view on the line 5—5 of Fig. 4;

Fig. 6 is a fragmentary side elevation, looking

2

from the right of Fig. 3, of the horn directional control and locking means;

Fig. 7 is an enlarged fragmentary top plan view of the horn and the mounting members at one side thereof;

Fig. 8 is an enlarged horizontal sectional view taken on the line 8—8 of Fig. 6;

Fig. 9 is a fragmentary side elevation of the horn and its supporting means, with portions broken away, showing quadrant means associated therewith and forming part of the directional control means;

Fig. 10 is an enlarged fragmentary end view, looking from the left of Fig. 9, showing the quadrant and one of the mounting members therefor;

Fig. 11 is an enlarged fragmentary end view, looking from the left of Fig. 9, showing the other of the mounting members for the quadrant;

Fig. 12 is an enlarged vertical transverse sectional view of the quadrant taken at a point approximately midway between the ends thereof;

Fig. 13 is an enlarged top plan view, partly in section, of the horn supporting means, and the quadrant means, illustrated in Fig. 9, with parts omitted for purposes of clearer illustration;

Fig. 14 is an enlarged horizontal section of directional indicating means embodying the present invention and illustrated in Figs. 1 and 6;

Fig. 15 is a section on line 15—15 of Fig. 14; and

Fig. 16 is a front elevation of said indicating means.

The novel horn supporting and directional control means of the present invention is particularly adapted for use with pneumatic sound projecting apparatus installed at airports, military and naval bases, ships, etc., for transmitting orders, instructions, or sound signals to airplanes, and to the personnel of said bases and ships.

Accordingly, the horn is herein illustrated as being mounted on a support 25 (Fig. 1) such as, for example, the deck of a ship, or the roof or platform of a control station at an airport.

As shown, the horn is rotatably supported by means of a novel construction comprising a long tubular mast 26 (Figs. 1, 3 and 4) having welded or otherwise suitably secured to the lower end thereof a relatively large base flange 27 which, in turn, is secured, as by bolts 28, to the upper

surface of support 25. Positioned within mast 26 is a tube 29 which is of a length such that the opposite ends thereof project beyond the opposite ends of said mast, the support 25 being provided with a suitable opening 30 to receive the lower 55 projecting end of said tube. The outer diameter

of tube 29 is materially less than the inner diameter of the mast.

Surrounding mast 26 and secured thereto near the upper end, as by bolts 31, is a flanged collar 32 (Figs. 1 and 4) adapted to support two vertically spaced roller bearings 33 and 34 which also surround the mast and are held in spaced relation by a sleeve 35. Bolts 31 are threaded through collar 32 and are formed with reduced end portions 36 that engage in suitable openings in the mast to firmly secure said collar to said mast. Bearings 33 and 34 rotatably support and guide a cylindrical housing 37 concentric with mast 26. At its upper end, housing 37 is secured to the upper projecting portion of tube 29, as by bolts 38, and extends downwardly therefrom and over bearings 33, 34 and the flange of collar 32. Bolts 38 are threaded through housing 37 and formed with reduced end portions 39 (Fig. 5) engaged in suitable openings in tube 29 to firmly secure said housing to said tube and against relative rotation. Tube 29 is thus rotatably supported by mast 26 through the above described housing 37, bearings 33, 34 and flanged collar 32. Housing 37 and tube 29 are held against upward displacement by a retaining ring 40 which is secured to the lower end of said housing, as by set screws 41, and provided within an inturned flange 42 that is disposed beneath the flange of collar 32. Ring 40 is assembled on mast 26 at the time collar 32 is engaged over said mast, the flange 42 of said ring being provided with an enlarged central opening 43 to permit the hub portion of collar 32 to extend therethrough.

Rigidly secured to the upper end of tube 29 above housing 37 is a yoke 44 (Figs. 1, 2 and 4) having a pair of transversely spaced, vertically and rearwardly extending arms 45 adapted to receive therebetween, and support, a trumpet or horn indicated generally at 46. Horn 46 may be of any suitable size or type, and is herein shown, for purposes of illustration only, as a multiple unit horn of the type illustrated and described in my copending application Serial No. 517,628, filed January 10, 1944. As illustrated, the horn comprises eight interconnected first and second throat sections 47 and 48 which are disposed in spaced parallel relation, and are bolted to a common junction body 49 having a bell 50.

In order to facilitate adjustment of the horn to a selected position in azimuth and elevation, means are provided for balancing the horn on arms 45 of the yoke. As shown, horn 46 has engaged over its throat sections 48 a circular plate 51 (Figs. 1, 2, 7 and 9) which is clamped to said sections adjacent the rear ends thereof by two-part clamps 52 secured to said plate. Welded or otherwise suitably secured to plate 51 are two diametrically disposed angle brackets 53 (Figs. 2 and 7) which extend rearwardly through said plate and have secured thereto, as by bolts 54, corresponding ends of oppositely disposed arms 55. Arms 55 extend from brackets 53 forwardly along opposite sides of horn 46 and have their corresponding opposite ends secured as by bolts 56, to the junction body 49 of said horn.

Horn 46 is positioned between arms 45 of yoke 44 and is pivotally mounted on said arms by studs 57 (Fig. 7) which are journaled in suitable bearings in the upper ends of the arms 45. Each stud has a reduced portion 58 that is threaded in a suitable opening 59 in arm 55. Openings 59 in arms 55 are so located that the portions of horn 46 extending forwardly and rearwardly of the pivot 57 will counterbalance each other. A bowed

spring washer 60 (Fig. 7) is inserted between the heads 61 of studs 57 and the adjacent surfaces of arms 45 to provide a frictional drag on the studs.

Novel means are provided for rotating tube 29 from a remote point whereby horn 46 may be conveniently moved in azimuth to any selected position, and the amplified sound may be propagated in a desired direction. As herein shown, said means preferably comprise a tube 62 (Figs. 1 and 3) having the same outside and inside diameters as tube 29, and which is connected with the latter through the medium of a coupling 63, thus forming an extension of tube 29. Coupling 63 is welded or otherwise suitably secured to the upper end of tube 62 and provided with an internally threaded portion 64 having threaded engagement with the lower threaded end of tube 29. To further secure tube 62 to tube 29 and prevent relative rotation of said tubes, coupling 63 is provided with one or more set screws 65 engaged with tube 29.

Tube 62 extends downwardly through the opening 30 in support 25, and is journaled in a suitable bearing in a bracket 66 (Figs. 1, 3 and 6) secured, as by bolts 67, to the underside of said support. Bracket 66 is preferably made in two parts to facilitate assembling of said bracket to tube 62, and removal of the same for repair or replacement purposes, the two parts of said bracket being bolted together by bolts 68. Tube 62 extends downwardly to a convenient operating point, and is rotated by a hand-wheel 69 which may be secured directly to the lower end of said tube, but, as herein shown, is preferably secured, as by bolts 70, to a housing 71 to be hereinafter described, said housing being secured, in turn, as by bolts 72, to the lower end of tube 62. Bolts 72 are threaded through the upper reduced portion of housing 71 and formed with reduced end portions 73 which engage in suitable openings in tube 62 to prevent rotation of said housing relative to said tube. By rotating hand wheel 69, tubes 62 and 29 will be rotated through housing 71, thereby effecting rotation of horn 46 about a vertical axis.

Novel means are provided for locking horn 46 in any selected positions in azimuth, and for limiting rotation of said horn about the vertical axis of its support to one revolution in opposite directions. As herein shown, said means preferably comprise a brake arm 74 (Figs. 6 and 8) pivoted on a stud 75 that is threaded in one side of the housing 71. Pivottally connected at 76 with the arm 74 is one end of a rod 77, the opposite end of which is pivotally connected at 78 with a dog 79. The latter is engaged in the forked upper end of an arm 80 and is pivoted intermediate the ends thereof on a stud 81 that is threaded in said arm. Arm 80 is formed integrally with a two-part bracket 82 that is clamped to tube 62 beneath bracket 66 as by bolts 83. When the dog is in the dotted line position of Fig. 6, rotation of tubes 62 and 29 by hand wheel 69 through housing 71, will impart a like movement to brake arm 74, rod 77, dog 79 and bracket 82.

As shown in full lines in Figs. 3 and 6, dog 79 is adapted to project into the space between any two teeth of a number of teeth 84 that are formed integrally with the bracket 66 and spaced around the lower end of said bracket. Engagement of dog 79 with the teeth 84 through upward movement of arm 74 and rod 77 will thus lock tubes 62, 29, and horn 46 against rotation by hand wheel 69. Disengagement of dog 79

from teeth 84 is effected by downward movement of arm 74 and rod 71.

Dog 79 is held in operative, or in disengaged positions by novel latch means comprising a pawl 85 (Fig. 8) which is adapted to be engaged in one or the other of two notches 86 and 87 (Figs. 6 and 8) that are formed in an arcuate plate 88 which is secured to and spaced from the housing 71 by bolts 89 and spacers 90. Pawl 85 is slidably mounted in a slot 91 formed in arm 74, and is yieldingly held against lateral movement relative to said arm by a disk 92 secured to said pawl by a screw 93. Connected with pawl 85 is one end of a rod 94 which extends through the hollow handle 95 of arm 74 and is provided on the opposite end thereof with a push button 96. Surrounding rod 94 and disposed within handle 95 and between the latter and the push button 96 is an expansion spring 97 for biasing the pawl 85 toward the plate 88. Notches 86 and 87 determine the operative and disengaged positions, respectively, of dog 79, and upon disengagement of pawl 85 from said notches through depression of push button 96, dog 79 may be moved by arm 74 into and out of engagement with teeth 84 to lock the horn in a selected position in azimuth.

Rotation of horn 46 as hereinbefore described, is limited to substantially 360° in opposite directions. For this purpose, the teeth 84 on bracket 66 include a tooth 98 (Figs. 3 and 6) which projects beyond the teeth 84, and may extend the full length of said bracket. When dog 79 is raised and held out of engagement with teeth 84, tooth 98 will be in the path of rotation of the dog and will be engaged by the latter, thereby limiting rotation of horn 46.

With the construction thus far described, horn 46 may be adjusted to any position about a vertical axis to direct the sound emanating therefrom in a desired direction in azimuth. It is desirable, however, that horn 46 be capable of adjustment in elevation about a horizontal axis also, whereby the sound emanating therefrom may also be directed upwardly or downwardly, as desired. Accordingly, novel means are provided for tilting horn 46 on its supporting mast, said means being operable from the same convenient point at which horizontal rotation is imparted to said horn. As shown, there is journaled in suitable bearings in housing 71 and in hand wheel 69 a vertically disposed stub shaft 100 (Fig. 3) having fixed thereon a worm 101. Disposed within hand wheel 69 and secured to the lower projecting end of shaft 100 is a hand wheel 102 preferably provided with a handle 103, for effecting rotation of shaft 100 and worm 101 in opposite directions. Worm 101 meshes with a worm wheel 104 which is fixed on a stub shaft 105 that extends transversely of housing 71 and is journaled in suitable bearings in said housing. Shaft 105 is disposed directly beneath tube 62 and has fixed thereon a drum 106. The central portion of a flexible cable 107 is wound around drum 106, and the end portions 108 and 109 of the cable extend from the drum up through tubes 62 and 29 to the top of the latter and then pass over and around suitable grooved sheaves 110 and 111, respectively (Fig. 9). Sheaves 110, 111 project through suitable slotted openings in housing 71 and tube 29 and are journaled on pins 112 (Fig. 5) carried by said housing. From the sheaves 110, 111, the cable portions 108, 109 extend upwardly in opposite directions, then toward each other beneath horn 46, and have their free-ends connected in a manner to be described, to a quadrant 113. The lat-

ter is disposed between the arms 45 of yoke 44, and comprises a curved, inverted V-shaped member 114 providing a guide for cable portions 108, 109, and having a cross brace 115 and a center brace 116 (Figs. 9 and 12), said braces being welded together and to said member.

The quadrant is secured to horn 46 to transmit to the latter the movements of cable portions 108, 109, whereby tilting of said horn upwardly or downwardly on yoke 44 is effected. Accordingly, member 114 has welded to one end thereof a vertical plate 117 (Fig. 10) which is secured, as by bolts 118, to the lower end of plate 51. Welded to the opposite end of member 114 is an L-shaped member 119 (Figs. 9 and 11) which extends upwardly between adjacent throat sections 48, and horizontally beneath horn 46, and is secured to said sections and the bell of said horn, as by bolts 120 and 121, respectively.

Cable portion 108 extends from sheave 110 upwardly along member 114, then horizontally beneath horn 46 through registering openings 122 (Fig. 10) formed in plates 117 and 51, and has its free end connected through the medium of a turnbuckle 123 with an anchor plate 124 which is welded to the cross brace 115 of quadrant 113 (Figs. 9 and 12). Cable portion 109 extends from sheave 111 upwardly along member 114, then horizontally beneath horn 46 through enlarged openings 125 and 126 (Figs. 11 and 13) formed in member 119, and has its free end connected through the medium of a turnbuckle 127 with plate 124. Cable portion 108 is maintained taut and in engagement with quadrant 113 by a grooved sheave 128 (Figs. 4, 9 and 13) journaled at 129 (Fig. 4) between a pair of arms 130 that are secured to opposite ends of a pin 131 that is rotatably mounted in yoke 44 and tube 29. Connected to arms 130 are pull springs 132, the opposite ends of which are connected with a U-shaped bracket 133 that is welded or otherwise suitably secured to yoke 44 between arms 45.

Upon rotation of drum 106 in one direction through the described driving means with hand wheel 102, the cable portion 108 will be wound upon said drum, and the cable portion 109 will be unwound therefrom, thereby shortening and lengthening said cable portions, respectively, and rotating horn 46 through quadrant 113 in a counter-clockwise direction as viewed in Fig. 1. When drum 106 is rotated in the opposite direction, the above-described winding and unwinding of cable portions 108, 109 will be effected in reverse order, and horn 46 will be rotated through quadrant 113 in a clockwise direction as viewed in Fig. 1. It will be noted that through association of the means for effecting rotation of horn 46 about a horizontal axis with the means for effecting rotation of said horn about a vertical axis, adjustment of the horn upwardly or downwardly may be effected in all positions of horizontal adjustment.

Novel indicating means are provided to facilitate adjustment of the horn to a selected position in a vertical plane. As shown in Figs. 14 to 16, said indicating means comprises a spur pinion 134 which is secured, as by a screw 135, to one end of drum shaft 105 exteriorly of housing 71. Pinion 134 meshes with a large spur gear 136 of a compound idler including a small spur gear 137. Gears 136, 137 are secured in a suitable manner to a stud 138 journaled in a bracket 139 secured to and spaced from the adjacent side of housing 71, as by bolts 140 and spacers 141. Bracket 139 is provided with an enlarged opening

142 to receive the hub of pinion 134 and to provide sufficient clearance for rotation of said pinion. Gear 137 meshes with a considerably larger spur gear 143 journalled on a stud 144 secured in bracket 139. Pinion 134, and gears 136, 137 and 143 are enclosed in a casing 145 engaged over bracket 139 and secured to housing 71.

Secured to gear 143, as by bolts 146, is a clip 147 which extends through a suitable opening 148 in casing 145, and has secured thereto, as by bolts 149, an indicator hand 150. Hand 150 cooperates with a segmental dial 151 secured to casing 145, as by screws 152, said dial being graduated in tens of degrees in opposite directions from zero. Gears 134, 136, 137 and 143 are so proportioned that hand 150 will have a movement imparted thereto equal in degrees to the degrees of rotation of horn 46, in a vertical plane, and this gearing is so arranged that the direction of movement of hand 150 will correspond to the direction of movement of said horn. When the horn is in zero position hand 150 will read zero on dial 151, adjustment of the hand being effected by inserting a screw driver or similar tool through a suitable opening 153 in casing 145, loosening screw 135 to free pinion 134, and permitting rotation of hand 150 to proper position.

Adjustment of horn 46 in elevation to a desired position may thus be quickly and accurately accomplished by rotating hand wheel 102 and observing the direction of rotation of hand 150 relative to dial 151, and movement of said hand to a desired position as indicated on said dial. To prevent damage to horn 46 through excess rotation thereof in opposite directions in elevation, spaced pins 154 are secured in casing 145 for engagement by clip 147 and hand 150 when the safe limit of rotation of said horn in either direction is reached. The "stop" positions are also indicated on dial 151.

The entire horn assembly may be steadied by guy wires (not shown) having corresponding ends thereof secured to support 25 and opposite ends secured to thimbles 155 (Figs. 1 and 9) carried by clamps 156 suitably attached to mast 26. Mast 23 may also be provided with vertically spaced steps 157 to enable ascending of the mast for purposes of repair or adjustment.

There is thus provided novel supporting and directional control means enabling location of a horn or other projector such as a light, at a high elevation, and rotation thereof from a remote point to a selected position in azimuth and elevation to direct the sound emanating therefrom. The present invention also embodies novel locking means for holding the horn in various positions of adjustment, and novel indicating means which eliminates all guessing on the part of the operator in adjusting said horn in a vertical direction to a desired position.

Although only a single embodiment of the invention has been illustrated and described in the foregoing specification, it is to be expressly understood that changes may be made therein particularly in the design and arrangement of the parts illustrated, without departing from the spirit and scope of the invention, as will now be clear to those skilled in the art. For a definition of the limits of the invention, reference is had primarily to the appended claims.

What is claimed is:

1. In apparatus of the class described, a support, a horn, means secured to said support and extending upwardly therefrom for supporting said horn at an elevation, and means operable

from a point beneath said support for rotating said horn relative to said support and said first-named means about vertical and horizontal axes to various positions to direct the sound emanating therefrom in a desired direction.

2. In apparatus of the class described, the combination of a fixed tubular mast, a tube within said mast and rotatably supported thereby, said tube extending above and below said mast, means connected with the lower end of said tube for rotating the latter in opposite directions, means for releasably locking said tube in various positions of rotation thereof and for limiting rotation of the tube to substantially one revolution in said directions, said last named means comprising a fixed annular member having a plurality of teeth and including one tooth which extends radially and axially beyond the others, a pivoted dog on said tube and rotatable therewith, an arm carried by said tube and connected with said dog for moving the latter into and out of engagement with said teeth, said dog upon disengagement thereof from the teeth being disposed in position to contact said tooth, and latch means for releasably holding said dog in engagement with and disengaged from said teeth.

3. In sound projecting apparatus, a support, a horn, means carried by said support and extending upwardly therefrom for supporting said horn at an elevation and for pivotal movement at said elevation about a horizontal axis, and means operable from a point beneath said support and connected with said horn for rotating the latter relative to said support and said first-named means about said axis to various positions.

4. In combination, a support, a horn, means carried by said support and extending upwardly therefrom for supporting said horn at an elevation and for pivotal movement at said elevation about a horizontal axis, means operable from a point beneath said support and connected with said horn for rotating the latter relative to said support and said first-named means in opposite directions about said axis to various positions, and means at said point for indicating the direction of rotation imparted to said horn and movement of the latter to a desired position.

5. In apparatus of the class described, the combination of a projector supported for pivotal movement about a horizontal axis, a quadrant secured to said projector, a flexible element having opposite ends connected with said quadrant, and means for operating said flexible element and said quadrant whereby rotation of said projector about said axis to various positions is effected.

6. In sound projecting apparatus, the combination of a vertically extending tubular support, a horn mounted on said support at the upper end thereof for rotation about a horizontal axis, a quadrant carried by said horn, a flexible element extending through said support and having opposite ends connected with said quadrant, and means at the lower end of said support and including a drum for operating said flexible element and said quadrant whereby rotation of said horn about said axis to various positions is effected.

7. In apparatus of the class described, the combination of a vertically extending tubular member, a horn mounted on said member at the upper end thereof for rotation about a horizontal axis, a quadrant secured to said horn, means for rotating said horn about said axis in opposite directions to various positions and comprising

ing a housing secured to the lower end of said tubular member, a drum rotatably mounted in said housing, a flexible element wound around said drum and extending upwardly through said member and having opposite ends thereof connected with said quadrant, and means for indicating the direction of rotation imparted to said horn and the movement of the latter to a desired position, said indicating means comprising a dial secured to said housing, a hand co-operating with said dial, and gearing between said drum and said hand for operating the latter from the former in a manner such that the direction and extent of rotation of said hand and said horn are identical.

8. In apparatus of the class described, a support, a horn, means secured to said support and extending upwardly therefrom for supporting said horn at an elevation, means operable from a point beneath said support for rotating said horn about a vertical axis to various positions, separate means operable at said point for rotating said horn in opposite directions about a horizontal axis to various positions, and means at said point and responsive to the operation of said last-named means for indicating the direction of rotation imparted to said horn by said last named means and the movement of the horn to a desired position.

9. In sound projecting apparatus including a horn, the combination of a fixed tubular mast, a tube within said mast and extending above and below the same, a yoke secured to the upper end of said tube for supporting said horn thereon, means for rotatably supporting said tube

on said mast and including a housing fixed on the tube and a pair of vertically spaced anti-friction bearings on the mast and engaged by said housing, and means associated with the lower end of said tube for rotating the latter and the horn carried thereby.

10 15 20 25 30 35 35

10. In sound projecting apparatus of the type embodying a horn, the combination of a fixed tubular mast, a tube within said mast and extending above and below the same, a yoke secured to the upper end of said tube for supporting said horn thereon, means for rotatably supporting said tube on said mast and including a pair of vertically spaced anti-friction bearings on the mast and a housing fixed on the tube and engaged over said bearings, means holding said housing and said tube against upward endwise displacement relative to said mast, and means associated with the lower end of said tube for rotating the latter and the horn carried thereby.

WILLIAM C. EAVES.
